[57] CLAIM

The ornamental design for a fuel dispensing cabinet, as shown and described.

DESCRIPTION

FIG. 1 is a front perspective view of a fuel dispensing cabinet showing my new design;

FIG. 2 is a front elevational view, shown with the access door in an open position;

FIG. 3 is a left side elevational view, the opposite side view being a mirror image;

FIG. 4 is a top plan view; and,

FIG. 5 is a rear elevational view.

The broken line showing of a coiled dispensing hose and associated equipment in FIG. 2 is for illustrative purposes only and forms no part of my claimed design.
